United States Patent Office

Des. 207,980
Patented June 20, 1967

207,980

SPACE HEATER

Joseph R. Mango, Midlothian, Ill., assignor to Temco Inc.,
Nashville, Tenn., a corporation of Tennessee

Filed Sept. 28, 1966, Ser. No. 4,059

Term of patent 14 years

(Cl. D81—19)

Fig. 1

Fig. 2

Fig. 3

FIGURE 1 is a perspective view of the space heater of my new design;

FIGURE 2 is a left end elevation view of the space heater of FIGURE 1;

FIGURE 3 is a top plan view of the space heater of FIGURE 1.

The rear and bottom of the space heater of my new design are substantially unornamented.

I claim:

The ornamental design for a space heater, as shown and described.
